UNITED STATES PATENT OFFICE.

EDWARD A. NISBET, OF PITTSBURGH, PENNSYLVANIA, ASSIGNOR TO INVINCIBLE VACUUM CLEANER MANUFACTURING COMPANY, OF PITTSBURGH, PENNSYLVANIA, A CORPORATION OF DELAWARE.

SUCTION CLEANER TOOL.

Application filed June 2, 1927. Serial No. 195,944.

This invention relates to suction cleaner heads or tools, and while not limited thereto, relates more particularly to a suction cleaner tool or head particularly designed for cleaning irregular surfaces such as the slotted floors of railway cars and the like, and due to its novel contour said tool is also particularly adapted to cleaning in corners and under low lying objects such as seats of railway cars and the like.

Another object of the present invention is to provide a tool of this class having a brush arranged annularly therein and adapted to loosen and stir up the dirt to be cleaned.

A further object is to provide a tool having a substantially triangular shape in plan, with three equal sides so that the brush may be removed and turned when its nose-point becomes worn, to present another of its three points, thereby permitting even wearing of the brush and greatly increasing its life.

A still further object is to provide a novel means for securing the head or tool to the suction tube of the cleaner which is simple in design and effective in operation.

In the drawings—

Figure 1 is a plan view of a tool constructed in accordance with my invention.

Figure 2 is a sectional elevation on the line III—III of Figure 1.

Figure 3 is a fragmentary sectional elevation on the line III—III of Figure 1.

The cleaning head A of this invention comprises a metallic body portion substantially triangular in plan and composed of a relatively flat top wall 3 and a depending peripheral flange 4. The wall 3 and flange 4 are formed integral and combine to form a triangular shaped receiving socket having three equal sides and adapted to receive a triangular brush member B.

The top wall 3 of the body portion of the cleaning head is provided with a centrally arranged opening 5 which communicates with

a suction conduit stub 6 formed integral with the top wall of the head A, and adapted to be secured to the end of the suction conduit or tube 2 of a suction cleaning apparatus.

The conduit stub 6 is of slightly greater diameter than the suction tube 2 of the cleaner so as to telescopically receive the end of the tube 2. The stub 6 is slotted longitudinally,

as at 7, from its free end inwardly for a portion of its length and is also slotted circumferentially, as at 8, from the slot 7, for approximately one-quarter of its circumference, the slots 7 and 8 intersecting and outlining a depressing or contracting tongue portion 9 in the side wall of the conduit stub 6 adapted to be contracted against the tube 2 and frictionally secure the head A on said tube. A lug 10 is formed integral with the tongue portion 9 of the stub 6 above the slot 7 and a second lug 11 is formed integral with the stub 6 below the slot 7, and a clamping screw 12 is passed freely through an aperture in the lug 10 and threaded into a threaded aperture in the lug 11. The screw 12 is adapted to force the lugs 10 and 11 toward each other to contract the tongue portion 9 of the stub and secure or lock the head A on the tube 2.

The brush B comprises a rigid triangularly shaped body portion 15 preferably composed of wood and which has its lower or bottom face cut away around its edge to form an annular horizontal flange portion 16 in which two or more rows of bristles 17 are mounted in the usual manner.

The interior of the brush body, that is, that portion within or surrounded by the bristles 17, due to the cutting away of the body to form the flange 16, projects downwardly a material distance along the inside of the bristles 17 for a purpose to be described.

The interior of the brush body is cut away to form a substantially triangular hollow suction dome 18 which terminates at its upper end in a circular outlet opening 19 which communicates through the opening 5 in the body of the head A with the suction conduit stub 6. The side walls of the dome 18 are inclined or flanged outwardly at a materially greater degree at the points of the dome 18 than intermediate such points, so as to more evenly distribute the suction throughout the dome.

The brush B is adapted to be removably secured in the head A by screws 20 which pass through openings in the top wall 3 of the head A and are threaded into the body of the brush B.

The interior portion of the brush body 15 which projects downwardly along the bristles 17 serves as a shield or skirt to deliver the

suction forces closer to the article being cleaned, while the bristles are free to flex outwardly.

The point of the suction head opposite to the suction conduit stub 6 forms the nose of the tool and the point of the brush B mounted in the nose point of the tool will be worn much quicker than the remainder of the brush, due to the tool being forced nose point first into corners and under objects. When the nose point of the brush becomes worn its efficiency becomes lessened and a new nose point is necessary. Due to the novel shape of the cleaning head and brush, when the nose point of the brush becomes worn, it is only necessary to remove the screws 20 and remove the brush from the head A, then rotate the brush one-third a revolution so as to locate one of the other points of the brush at the nose point of the head and then remount the brush. The above operation may be repeated until all of the three points of the brush have become worn, and results in a materially longer life of the brush and also, in a more even wearing of the brush.

The bristles of the brush B are of material length so as to extend into the slots or depressions in the floor of a railway car or similar structure. It is well known that the slotted floors of railway cars and the like become partly, and sometimes wholly, filled with dirt and foreign matter carried into the cars by passengers. The brush of the present invention will loosen the foreign matter and when pressed into the slots or depressions, serves as a flexible skirt to cause the suction forces to be confined to the area within the cleaning head so that a strong suction is had to lift the heavy particles of foreign matter out of the grooves of a car floor.

While I have shown and described one

specific embodiment of my invention, it will be understood that I do not wish to be limited thereto, since various modifications may be made without departing from the scope of my invention as defined in the appended claim.

I claim—

A cleaning head for a suction cleaning apparatus comprising, in combination, a body portion substantially triangular in plan and composed of a relatively flat top wall and a depending peripheral flange, which wall and flange combine to form a triangular receiving socket having substantially three equal sides to receive a triangular shaped brush member, said top wall of said body portion being provided with a centrally arranged opening communicating with an integrally formed connecting conduit adapted to be connected to the suction conduit of a cleaning apparatus, said brush comprising a substantially triangular rigid body portion adapted to fit within said body portion of said head, a row of bristles secured in and adjacent the outer edge of said body portion of said brush, the portion of said brush body within said bristles extending downwardly a material distance along and terminating short of the lower ends of said bristles and having its central portion cut away so as to form a skirt flange within said row of bristles and a hollow suction dome terminating in a centrally arranged opening communicating with the opening in said top wall of said body portion of said head, and means for removably securing said brush in said body portion of said head.

In testimony whereof, I have hereunto signed my name.

EDWARD A. NISBET.
